UNITED STATES PATENT OFFICE.

WILHELM SCHWEITZER, OF BRESLAU, GERMANY.

FLOOR-SCRAPER.

1,149,864.

Specification of Letters Patent.

Patented Aug. 16, 1915.

Application filed October 29, 1913. Serial No. 798,145.

To all whom it may concern:

Be it known that I, WILHELM SCHWEITZER, a subject of the King of Prussia, German Emperor, residing at Breslau, Kingdom of Prussia, German Empire, have invented certain new and useful Improvements in Floor-Scrapers, of which the following is a specification.

This invention relates to a floor scraper by means of which floors can be rubbed, waxed and polished without any fatigue for the person who handles the apparatus.

In the accompanying drawings: Figure 1 is a front elevation partly in section of the apparatus. Fig. 2 is a plan view of the same. Fig. 3 is a cross section on line A—A of Fig. 1. Figs. 4 to 6 represent the tools for working the floor. Fig. 6 shows, on a larger scale, the part of the tool represented in Fig. 5.

The apparatus essentially consists of a casing 3 of U-shaped cross section mounted upon wheels 1—2. This casing 3 has rails 4 at its lower end on the inner surface. The tool holder 5, guided on said rails 4 consists of a rectangular frame, which has lateral arms 6 adapted to slide upon the rails 4 of the casing. Plates 7 fixed on the inner surfaces of the longitudinal sides of the tool holder 5, have vertical slots 8 extending downward from their upper edges (Fig. 1). The tool holder 5 is driven from the wheels 1 the revolving motion of said wheels being transformed into a reciprocating motion of the tool holder through the intermediary of the driving rods 9.

A pushing rod 12 the lower end of which is hingedly mounted in a support 10 of the casing 3 has a handle 11 at its free end. A supporting rod 13 is hingedly mounted upon the rear end of the casing 3, has a fork-shaped end adapted to engage with laterally projecting studs 13 of the pushing rod 12. When the apparatus is to be moved to and fro on the floor for working the same the supporting rod 13 is lowered so that the pushing rod is free.

For rubbing the floor the tools shown in Figs. 1 and 3 are used which consist of steel shavings compressed or tied up in any convenient manner so that they form prismatic blocks 15. In each block 15 an iron rod 16 is embedded the ends of which laterally projecting from the block 15 are adapted to engage with the vertical slots 8 (Fig. 1) of the tool holder. The blocks 15 are of such

a size that if the lower surface of the block rests upon the floor the ends of the iron rods 16 stand at a certain distance above the lower ends of the vertical slots 8 so that the diminution of the mass of the block is automatically compensated as said iron rod 16 descends in said slots 8. The required pressure is obtained by a heavy lid 19 resting upon said blocks 15 and having a handle 17 and rollers 18. In order to remove the blocks of steel shavings 15 the lid 19 is pulled in the direction of the arrow (Fig. 1) its rollers 18 running on the upper edges of the plates 7. After the floor has been rubbed it is waxed by means of brushes 20 and a wax distributing device 21, then polished by the brushes only.

The brushes 20 have lateral studs 22 and the wax distributing device 21 has similar studs 23 designed to be inserted in the vertical slots 8 of the plates 7 of the tool holder. The wax distributing device 21 is mounted at the middle of the tool holder, a brush 20 being placed at the front end and another brush at the rear end of said tool holder. The wax distributing device 21 consists of a receptacle 25 (Fig. 5) closed by a lid 24 and connected by means of a regulating valve 26 with a tubular distributor 27. This tubular distributor is fixed and has holes 28 (Fig. 6) through which the liquid wax flows out upon the floor. The liquid wax is continuously stirred by means of stirrers 29 fixed upon a shaft 30 revolvably mounted in the ends of the tubular distributor 27, said shaft being turned by means of friction wheels 31 mounted on its ends and rolling upon the floor. After the floor has been waxed the distributing device is removed and a polishing brush 20 inserted instead.

I claim:

1. A floor scraper comprising in combination a casing of U-shaped cross section mounted on wheels, guide rails fixed at the lower end on the surface of said casing, a rectangular tool frame movably mounted on said rails, means for communicating a reciprocating motion from the wheels of the casing to said tool holder frame, plates having vertical slots downwardly extending from the upper edge fixed on the inner surfaces of the long sides of the tool holder frame, and tools removably mounted in said vertical slots of the tool holder frame so that they are pressed on the floor by gravity,

substantially as described and shown and for purpose set forth.

2. A floor scraper comprising in combination a casing of U-shaped cross section 5 mounted on wheels, guide rails fixed at the lower end on the inner surface of said casing, a rectangular tool frame movably mounted on said rails, means for communicating a reciprocating motion from the 10 wheels of the casing to said tool holder frame, a handle for pushing said apparatus, plates having vertical slots downwardly extending from the upper edge fixed on the inner surfaces of the long sides of the tool

holder frame, and the scraper tool loosely 15 mounted in said tool holder and consisting of blocks of compressed steel shavings, horizontal rods embedded in said blocks so that their projecting ends can engage with the vertical slots of said plates of the tool holder frame, substantially as described and shown 20 and for the purpose set forth.

In witness whereof I have hereunto set my hand in the presence of two witnesses.

WILHELM SCHWEITZER.
